POWER TRANSMISSION

Frederick S. Hodgman, Glen Rock, N. J., assignor,
by mesne assignments, to The Waterbury Tool
Company, Waterbury, Conn., a corporation of
Connecticut

Application August 25, 1936, Serial No. 97,791

7 Claims. (Cl. 255—19)

This invention relates to power transmissions and particularly to transmissions of the hydraulic type comprising a fluid pump and fluid motor either or both of which may be provided with mechanism for varying its displacement in order to vary the speed ratio between the prime mover which operates the pump and the load device which the motor operates. The invention is illustrated as adapted for use in a well drilling rig of well-known type in which a string of drill stem is caused to revolve by a rotary drilling head while a portion of the weight of the string rests upon the earth formation at the bottom of the hole being drilled, the remainder being suspended in a block and falls mounted in a drilling derrick and connected to a draw-works drum.

It is desirable in such drilling operations to maintain at a constant value that portion of the weight of drill string which rests upon the earth formation at the bottom of the hole and to be able to readily adjust such weight to different values as different formations are encountered. Various systems have been proposed for automatically regulating the weight on the drill stem in such a manner. Systems of this character as heretofore constructed have utilized either the energy of the drill stem itself for feeding the same into the hole as required; such, for example, as systems wherein a friction or fluid brake is automatically regulated to maintain a constant tension on the draw-works drum, or have utilized an expensive and cumbersome power operated feed system such as a steam or electric powered feed controlling apparatus. Devices of the latter class are not only expensive in first cost and in operation but are open to other objections in that they require specially trained operators or are incapable of use in fields where an adequate water supply is not available.

It is an object of the present invention to provide a well drilling rig whereby the weight of the drilling bit on the earth formation at the bottom of the hole may be maintained at a constant but adjustable value and which incorporates simple, reliable and inexpensive apparatus capable of operation in any locality by untrained operators.

A further object is to provide a well drilling rig of this character including a feed controlling device which may be energized from a small prime mover independently of the principal source of power for the draw-works and other apparatus usually associated with drilling rigs of the rotary type and which small prime mover may preferably comprise a small internal combustion

engine of the type used in motor vehicles which are readily available at low cost.

It is a further object to provide a feed controlling apparatus for a well drilling rig wherein a hydraulic variable speed power transmission is incorporated for transmitting power between a substantially constant speed prime mover and the draw-works drum, whereby the speed of rotation of the drum may be precisely controlled automatically to maintain a predetermined constant weight on the drill bit and whereby also the draw-works may be operated from the auxiliary prime mover to raise or lower the drill string in an emergency.

Further objects and advantages of the present invention will be apparent from the following description, reference being had to the accompanying drawings wherein a preferred form of the present invention is clearly shown.

In the drawings:

Fig. 1 is a plan view partly in section of a well drilling rig showing a preferred form of the present invention.

Fig. 2 is a cross section on line 2—2 of Fig. 1.

Fig. 3 is a cross section on line 3—3 of Fig. 1.

Fig. 4 is a fragmentary detail view of a portion of the apparatus.

Referring now to Fig. 1 there is illustrated a draw-works having a drum 10 journalled in bearings 12 and adapted to have wound thereon a cable by which a drilling string may be supported from a derrick, not shown, in the usual manner. The drum 10 is keyed to a shaft 14 on which is splined a slidable clutch member 16 which may be engaged with a sprocket 18 freely rotatable on the shaft 14. At its opposite end the shaft 14 carries splined thereon a slidable clutch member 20 engageable with a gear 22 freely rotatable on the shaft 14. The sprocket 18 is driven by a chain 24 from a suitable prime mover, not shown, through the medium of any suitable multiple speed transmission mechanism. The sprocket 18 carries a hub 26 on which is splined a slidable clutch member 28 engageable with a sprocket 30, freely rotatable on the hub 26. The sprocket 30 drives by means of a chain 32, a sprocket 34 keyed to a shaft 36 which carries a bevel pinion 38 meshing with a bevel gear on the under side of a rotary table 40 whereby the drill stem may be given a rotary movement independent of the vertical movement imparted to it by the draw-works drum 10, as is well-known in the art.

The gear 22 is adapted to be driven from a fixed displacement fluid motor 42 through the medium of a pinion 44 and intermediate gearing 55

46. The motor 42 is connected by means of a high side conduit 48 and a low side conduit 50 with a variable displacement fluid pump 52 which has its input shaft 54 connected by means of reduction gearing 56 to the crankshaft of an internal combustion engine prime mover 58.
- 5 The pump 52 and motor 42 are illustrated as of the well-known "Waterbury" construction as shown in Fig. 2. The pump 52 includes a revolving cylinder 60 within the bores 62 of which pistons 64 are reciprocated by the motion of a socket ring 66 which revolves in a tilting box 68. The tilting box 68 carries a stud 70 having a pivoting and sliding connection with the piston 72 of a fluid motor 74. The socket ring 66 is caused to revolve with the shaft 54 by a universal joint connection, not illustrated, while the cylinder barrel 60 is keyed to the shaft 54. The tilting box 68 is mounted for oscillatory movement 10 on trunnions 76 in the casing 78 of pump 52.
- 10 When the tilting box 68 and consequently the socket ring 66 are tilted about the trunnion 76 and shaft 54 is caused to revolve, the pistons 64 are reciprocated in the bores 62 due to the inclination of the plane of rotation of the socket ring 66 to the plane of rotation of the cylinder barrel 60, the stroke of the pistons 64 being determined by the angular setting of the tilting box 68. As pistons 64 are reciprocated, fluid is caused to be 15 drawn into the cylinders 62 through one arcuate port, not shown, in the valve plate 80 and to be expelled from the cylinders 62 through the opposite arcuate port in the valve plate 80. Customary replenishing and relief valves, not shown, are incorporated in the valve plate 80 for the purpose of maintaining the working circuit filled with fluid at all times and for preventing building up of excessive pressure and undue overloading of the machine.
- 20 The fluid motor 42 is similar in construction to the pump 52 except that its socket ring is journaled in a fixed angle box so that the stroke of its pistons is fixed. Fluid delivered from the pump 52 through one of the ports of the valve 25 plate 80 and through conduit 48 is admitted to the cylinders of the motor 42 through arcuate port 82 in the motor valve plate 84, while on the return stroke of the pistons of the motor 42 fluid is returned to the pump through port 86 of motor 30 valve plate 84 and through low side conduit 50 to the opposite arcuate port in the valve plate 80. The construction and operation of hydraulic transmissions of this character are well-known in the art so that further description thereof is 35 unnecessary.
- 40 The valve plate 84 is provided with conduits 88 and 90 forming a by-pass from the high pressure port 82 to the low pressure port 86 which is under the control of a valve 92 operable by means of bevel gearing 94, shafts 96, bevel gearing 97 and handwheel 98 from a position adjacent the driller's post.
- 45 The fluid motor 74 includes a cylinder 100 within which is freely reciprocable a piston 102 mounted on the piston rod 72. A conduit 104 connects the left-hand end of the cylinder 100 with the high side conduit 48. At the opposite end of the piston rod 72 a guide piston 106 is formed, against which abuts a spring 108 which 50 is adjustable by means of a spring plate 110 and adjusting screw 112. The latter is operable by means of bevel gearing 114, shaft 116 and handwheel 118 from a position adjacent the driller's post.
- 55 Adjacent the periphery of the gear 22 a locking 55
- 60 detent 120 is pivoted at 122 and carries a lever 124 to which is connected a piston 126. Piston 126 is reciprocable in a cylinder 128 having its lower end connected by a conduit 130 to the high side conduit 48. A spring 132 biases the piston 126 downwardly, and consequently urges the detent 120 into gear-engaging position whenever pressure in the conduit 48 is insufficient to overcome the force of the spring 132.
- 65 In operation assuming the drill string to have 10 been run into the hole, and the apparatus arranged for drilling operation; the clutch member 16 having been adjusted to disengage the sprocket 18, the clutch member 20 having been engaged with the gear 22, and clutch member 28 having 15 been engaged with sprocket 30, the rotary table is driven from the principal power source of the drilling rig through chain 24, sprocket 18, clutch 28, sprocket 30, chain 32, sprocket 34, shaft 36 and pinion 38. With the prime mover 58 running at a substantially constant speed the pinion 44 will be caused to turn at a speed determined by the position of the tilting box 68, which is in turn governed by the position of the piston 102. Assuming the drill string to be lowered sufficiently 20 so that its entire weight rests on the bottom of the hole, the spring 108 will urge the piston 102 to the left in Fig. 2, thus moving the tilting box 68 into stroke in a direction causing drum 10 to rotate in the hoisting direction.
- 25 As soon as the weight of the drill string comes on the drum 10, a resisting pressure is built up in the conduit 48, which pressure is transmitted through the conduit 104 to the cylinder 100 and piston 102. Depending on the adjustment of the 30 screw 112 and the valve 92, the piston 102 will begin to move to the right in Fig. 2 when a certain portion of the weight of the drill stem is suspended on the drum 10. The exact weight which it is desired to support during drilling operations 40 may be determined by suitable adjustments of the amount of opening of valve 92 and of the spring force of spring 108. Under certain conditions it is desirable to operate with the pump 52 having its tilting box maintained in a substantially 45 neutral position so that as fast as the drilling bit "makes hole", the weight of the drill string causes the motor 42 to operate as a pump, the entire output of which is passed through the by-pass 88-90. For this purpose an indicator 138 is 50 pivoted on a bracket 140 to move over a scale 142. One end of the indicator 138 is connected to an extension rod 144 passing through the end wall of the cylinder 100 and connected to the piston 102. By observing the position of the indicator 55 138 the operator may adjust the opening of the valve 92 so that the piston 102 rests in mid-position wherein the tilting box 68 is at no stroke. Should the bit "make hole" at a faster rate the increased weight on the drum 10 causes the pressure in conduit 48 to rise, thus moving piston 102 to the right and causing fluid to be pumped by pump 52 from conduit 48 to conduit 50 at a slow rate. The motor 42 is thereby permitted to turn faster to make up for this quantity which 60 formerly went through by-pass 88-90. Conversely, if the bit "makes hole" at a slower rate, the pressure falls slightly in conduit 48 causing piston 102 to move to the left and add a small quantity to the fluid pumped into conduit 48 by 65 motor 42. Since by-pass 88-90 is the only path from conduit 48 to conduit 50, the motor 42 will be slowed down to permit the additional fluid from pump 52 to go through the by-pass.
- 70 The weight maintained on the drilling bit may 70

be read from the usual weight gauge, not shown, or from a pressure gauge 146 in the line 130. This weight may be varied by varying the adjustment of the spring 108 by means of the hand-wheel 118.

- 5 Should it become necessary for any reason such as failure of the principal source of power to lift the drill string by means of the auxiliary prime mover 58, this may be done by closing the valve 92 10 and by tightening the adjustment of the spring 108 sufficiently so that it exerts a force to the left greater than the force exerted on the piston 102 when the entire weight of the drill string is suspended by the drum 10. Under these conditions 15 the piston 102 moves to the left, throwing the tilting box 68 into stroke in the hoisting direction and the drill string is then lifted at a rate determined by the setting of the adjusting screw 112 in relation to the weight of the drill stem.
- 20 Under other conditions it may be desirable to operate with the by-pass 88—90 completely closed. A constant weight may be maintained on the drilling bit under these conditions by suitable adjustment of the screw 112 such that the piston 102 is 25 permitted to move to the right of mid-position sufficiently to place the tilting box 68 in stroke in a lowering direction and to feed the drill stem downwardly at a rate corresponding to the rate at which the hole is being drilled. Under these conditions also, the feed is varied automatically to 30 follow exactly the rate of drilling. Should the drill be fed downwardly too fast, a greater proportion of the weight of the drill string would be supported on the earth so that the pressure in 35 conduit 48 is decreased, thus permitting piston 102 to move to the left reducing the rate of downward feed until a stable condition is reached. Likewise, if the downward feed be too slow for the rate of drilling, a greater proportion of the weight be- 40 comes suspended on the draw-works drum 10 so that the pressure in conduit 48 is increased, thus moving the piston 102 to the right and increasing the rate of downward feed correspondingly.

45 Should a failure in the prime mover occur at any time or should any accidents befall the hydraulic transmission so that pressure cannot be maintained in the conduit 48, the spring 132 is permitted to expand, moving the detent 120 into engagement with the gear 22, thus preventing the 50 drill string from dropping into the hole causing a "twist-off" or other serious difficulty.

It will be noted that with any given setting of the adjusting screw 112 the rate of feed and the weight supported may be adjusted over a limited 55 range by changing the setting of the by-pass valve 92. The spring 108 being of finite length will exert slightly less force when it is extended than when it is compressed due to the well known 60 relation between force and displacement of such a spring. If, then, the by-pass valve 92 be opened wider, the piston will have to move to the left thus permitting spring 108 to expand somewhat thereby decreasing the pressure to which motor 74 65 regulates the pump 52. Conversely, if the by-pass valve 92 be further closed the piston 102 will have to move to the right thus increasing the pressure in conduit 48. In practice, the length of spring 108 is made large relative to the range of 70 travel of piston 102 so that this variation in fluid pressure to which the pump 52 is regulated is rather small and substantially negligible in normal operation at any one setting. The adjustment of by-pass valve 92, however, provides a con- 75 venient means whereby a finer or vernier adjust-

ment of the weight supported may be obtained when desired.

While the form of embodiment of the invention as herein disclosed, constitutes a preferred form, it is to be understood that other forms might be adopted, all coming within the scope of the claims which follow.

What is claimed is as follows:

1. In a well drilling rig the combination of a drill string, a draw-works drum, a prime mover, a variable speed power transmission including a variable displacement pump and a fluid motor operable thereby connected in driving relation between the prime mover and the draw-works drum, a controlling member responsive to variations in fluid pressure produced by changes in torque imposed on the drum by the drill string, means whereby said controlling member may vary the speed ratio of the power transmission, and means including a restricted, adjustable by-pass from the high to the low side of said transmission for varying the weight supportable from said draw-works drum.

2. In a well drilling rig the combination of a drill string, a draw-works drum, a prime mover, a variable speed power transmission including a variable displacement pump and a fluid motor operable thereby connected in driving relation between the prime mover and the draw-works drum, a controlling member movable in accordance with variations in fluid pressure produced by changes in torque imposed on the drum by the drill string, means whereby said controlling member may vary the speed ratio of the power transmission, and means responsive to pressure failure in the high side of said transmission for preventing unwinding movement of said draw-works drum.

3. In a well drilling rig the combination of a drill string, a draw-works drum, a prime mover, a variable speed power transmission including a variable displacement pump and a fluid motor operable thereby connected in driving relation between the prime mover and the draw-works drum, a controlling member movable in accordance with variations in fluid pressure produced by changes in torque imposed on the drum by the drill string, means whereby said controlling member may vary the speed ratio of the power transmission, means for locking said draw-works drum against retrograde movement and means effective while normal operating conditions prevail for holding said last means inoperative.

4. In a well drilling rig the combination of a drill string, a draw-works drum, a prime mover, a variable speed power transmission connected in driving relation between the prime mover and the draw-works drum, means responsive to variations in torque imposed on the draw-works drum for controlling the speed ratio of the power transmission to feed the drill string downwardly at a rate to maintain a constant proportion of its weight suspended by the draw-works drum, means for locking said draw-works drum against retrograde movement and means effective while normal operating conditions prevail for holding said last means inoperative.

5. In a well drilling rig the combination of a drill string, a draw-works drum, a prime mover, a variable speed power transmission including a variable displacement pump and a fluid motor operable thereby connected in driving relation between the prime mover and the draw-works drum, means responsive to variations in torque imposed on the draw-works drum for controlling the speed ratio of the power transmission to

feed the drill string downwardly at a rate to maintain a constant proportion of its weight suspended by the draw-works drum, and means responsive to pressure failure in the high side of

5 said transmission for preventing unwinding movement of said draw-works drum.

6. In a well drilling rig the combination of a drill string, a draw-works drum, a fluid motor operatively connected to said drum, means for

10 by-passing a variable predetermined quantity of fluid from the high to the low side of said motor when a predetermined unwinding torque is exerted on said draw-works drum by said drill

string, and means for maintaining a constant pressure on the high side of said motor.

7. In a well drilling rig the combination of a drill string, a draw-works drum, a fluid motor operatively connected to said drum, means for

5 by-passing a variable predetermined quantity of fluid from the high to the low side of said motor when a predetermined unwinding torque is exerted on said draw-works drum by said drill string, and means including a pressure controlled 10 variable displacement pump for maintaining a constant pressure on the high side of said motor.

FREDERICK S. HODGMAN.
